UNITED STATES PATENT OFFICE.

EDGAR R. WRIGHT, OF GLENROCK, WYOMING.

OIL BURNER.

Application filed September 17, 1923. Serial No. 669,241.

To all whom it may concern:

Be it known that I, EDGAR R. WRIGHT, a citizen of the United States, residing at Glenrock, in the county of Converse and State of Wyoming, have invented certain new and useful Improvements in Oil Burners, of which the following is a specification.

This invention relates to oil burners, and particularly to that type of burner wherein an admixture of oil and air or steam is utilized.

An object of the present invention is to provide a burner which is adjustable at the nozzle and which does not require the reduction in pressure in the burner for controlling the outlet of the fluids passing through the burner.

Another object of the invention is to provide a burner casing constructed to receive oil and steam, and which has an oil passage so disposed within the steam passage as to preheat the oil from the steam as the latter passes through the burner.

A further object of the invention is to provide a burner which will thoroughly admix the compressed air or steam with the oil and will thoroughly break up and atomize the oil as it passes from the end of the burner to thus produce a hotter flame and to conserve the fuel in its consumption.

The invention still further aims at the provision of a burner which is capable of use with various grades of oil and which may be quickly and easily adjusted for taking care of a heavy oil or a light oil, the adjustment being a relatively simple one and requiring but little if any skill on the part of the operator.

The above and various other objects and advantages of this invention will be in part described in and part understood from the following detailed description of the present preferred embodiment, the same being illustrated in the accompanying drawing wherein:

Fig. 1 is a vertical central section taken through an oil burner constructed according to the present invention.

Fig. 2 is a top plan view thereof.

Fig. 3 is a detail side elevation of the sleeve valve for adjusting the spray in the burner, and

Fig. 4 is a transverse section through the burner casing substantially on the line 4—4 of Fig. 1.

Referring to the drawing 10 designates a burner casing in the form of a tube externally screw threaded for the reception, on its upper end, of a cap 11 which is provided with a burner slot 12 of suitable form and width. The tube 10 at its lower end is threaded into a hollow body 13 providing a casing for the reception of steam or compressed air which may be introduced to the casing 13 by a pipe 14 having an elbow 15 which is threaded through a plug 16 mounted in one side of the casing 13.

An oil pipe 17 is arranged lengthwise within the tube 10 and is of considerably less diameter to provide, between the tubes 10 and 17, an annular passage between the pipes.

The lower end of the tube 17 is threaded in an elbow 18 which is located centrally within the casing 13 and which is threaded upon one end of a spud 19, which latter is threaded through a plug 20 mounted in another side of the casing 13. Another elbow 21 is threaded into the outer end of the spud 19 for connection with an oil supply pipe 22. The spud 19 is provided with a jamb nut 23 which is on its outer end and arranged to bind against the outer side of the plug 20 for holding the tube 17 in an upright central position in the casing of the burner.

A plug 24 is threaded in the upper end of the tube 17 and the tube is provided at suitable points with spray openings 25 through which oil passing up through the tube 17 may escape. The oil issuing from the openings 25 is delivered directly into the draft of air or steam which is flowing upwardly through the outer tube 10, and such flow of oil is regulated by a sleeve valve 26 which is mounted to slide about the upper end of the tube 17. The tubular valve 26 has openings 27 therein adapted to register more or less with the openings 25. The sleeve valve 26 is supported upon the tube 17 by a rod 28 which is secured at its upper end to one side of the valve 26 and which extends downwardly to a point beneath the elbow 18 where the rod 28 is offset inwardly at 29 to dispose the lower end of the rod coaxially with the tubes 10 and 17 and with a stuffing box 30 in the bottom of the casing 13 through which the rod 28 extends. The casing 13 is provided with a frame 31 which depends about the stuffing box 30 and which is provided with a pair of spaced

apart bars 32 between which operates a thumb nut 33 threaded upon the lower end of the rod 28. The rod 28 is threaded for a considerable distance so as to adjust the rod vertically through the thumb nut 33. The thumb nut is held between the bars 32 and supported upon the lower bar when the weight of the sleeve 26 is taken up by the rod 28.

10 In operation, steam is admitted under pressure through the pipe 14 into the casing 13 and from there into the pipe 10, the steam issuing through the slot 12 and the cap 11 and heating the inner pipe 17 and 15 its contents. Oil is admitted from the pipe 22 into the central pipe 17 and is preheated before it reaches the nozzle openings 25. The preheated oil passes out through the openings 25 and the thumb nut 23 is turned 20 to adjust the sleeve valve 26 and register the openings 27 of the sleeve valve more or less with the openings 25 of the pipe 17. This controls the amount of spray without reducing pressure or fluid in either the 25 steam line or the oil line. There is consequently always a predetermined pressure of oil at the nozzle and no adjustment of the main valves is necessary.

It will be noted that the oil in the pipe 30 17 throughout its entire length is surrounded by the hot steam so that the oil passing into the casing is thoroughly heated and may thus be more easily vaporized. The thumb button 32 may be quickly and easily adjusted 35 so as to not only obtain the maximum efficiency in atomizing the oil and mixing it with steam, but also to quickly change the size of the nozzle openings for accommodating either a heavy grade of oil or a 40 light grade of oil.

The above specifically described embodiment of this invention may be changed and modified to meet various requirements and designs in manufacture and installation 45 without departing from the spirit of this invention, the modifications and changes are restricted only by the scope of the following claims.

1. An oil burner comprising an elongated 50 casing having a burner opening in one end and a steam inlet pipe in its other end, an oil pipe projecting into the casing and extending axially therein and being closed at its outer end and having laterally disposed 55 openings therein for spraying the oil from the tube, a sleeve valve surrounding the tube and slidably longitudinally thereon and having similar openings adapted to register with

the openings in the tube, and adjusting means for the sleeve valve operable exteriorly of the casing for moving the sleeve longitudinally upon the tube and adjusting the openings into and out of register with each other.

2. An oil burner comprising a tube, a steam pipe connected to one end for supplying steam to the tube, a second tube arranged in the first tube and adapted to receive oil to be heated by the steam, a cap closing the top of the first tube, a plug closing the upper end of the inner tube, said inner tube having a plurality of openings in its side through which the oil is adapted to be sprayed into the steam, a cylinder valve movably mounted on the inner tube for movement longitudinally thereon and having openings therein adapted to register with the openings in the tube, a rod connected to the cylinder valve and extending downwardly through the lower end of said outer tube, and a manually operable device connected to said rod for operating the same to shift the cylinder valve longitudinally upon the inner tube and change the relation between the openings of the inner tube and the cylinder valve.

3. An oil burner comprising a casing, a tube connected at one end to the casing, a steam pipe connected to the casing for supplying steam thereto and to said tube, a cap closing the other end of the tube and having a slot therein through which said steam may issue, a second tube arranged within the first and connected through the casing with a source of oil supply, a plug closing the outer end of said inner tube and the inner tube having a group of lateral openings in its outer end portion through which oil is adapted to spray into the steam, a perforated sleeve surrounding said apertured portion of the inner tube and slidably longitudinally thereon, a rod connected to said sleeve and extending downwardly through the casing, a stuffing box carried by the casing and surrounding said rod for packing the same, said rod being threaded upon its lower end exteriorly of the casing, a thumb nut threaded on the rod, and abutment means mounted on the casing and engaging opposite sides of the nut for anchoring the same whereby turning of the nut is adapted to move said rod and sleeve longitudinally and change the relative positions of the openings in the inner tube and the sleeve.

EDGAR R. WRIGHT.
